UNITED STATES PATENT OFFICE.

ANDREW RINGMAN, OF CHICAGO, ILLINOIS.

EYE-SHADE.

1,325,581.

Specification of Letters Patent. Patented Dec. 23, 1919.

Application filed August 10, 1918. Serial No. 249,226.

To all whom it may concern:

Be it known that I, ANDREW RINGMAN, a citizen of the United States, and a resident of Chicago, in the county of Cook and State 5 of Illinois, have invented certain new and useful Improvements in Eye-Shades; and I do hereby declare that the following is a full, clear, and exact description thereof, reference being had to the accompanying 10 drawings, and to the letters of reference marked thereon, which form a part of this specification.

This invention relates to improvements in eye shades and consists in the matters hereinafter more fully described and claimed and illustrated in the accompanying drawing.

Eye shades are used, primarily, in the presence of high artificial light, in doing 20 reading or clerical work, such as is done by bookkeepers, accountants, etc. The shade must be very light in weight, relatively cheap and of a construction that will be so easy upon the wearer as to not irritate him 25 or annoy him in the performance of his work. Eyeshields have heretofore commonly been made crescent shaped, of cardboard or other material, the edges bound with some suitable fabric, sometimes with 30 wire, and the device held to the forehead of the wearer by means of laterally and rearwardly extending wire arms, such as are used on spectacles.

One of the objections to such devices has 35 been the crescent shape of the shade, as a whole, tapering upwardly from the bottom toward the side,—which, while shielding the eyes of the wearer from the direct or frontal rays of light, permit the light to impinge 40 at the sides. Another objection to such devices has been the nature of the binding at the upper part of the shield, where the binding edge lies directly upon the forehead of the wearer, and, when the shield is held 45 sufficiently close and tight to be retained in position, makes a ridge or indentation in the forehead to the annoyance and irritation of the wearer, and the interference with his work.

50 One of the objects of my invention is to produce a shield which will obviate the objections aforesaid and which, at the same time, will embody a shield of neat appearance, light weight, and one which may be 55 firmly fastened in position upon the fore-

head of the wearer with a yielding cushion between the shield and forehead.

To these ends, the invention is shown in the accompanying drawing, in which—

Figure 1 illustrates a front view of an 60 improved eye-shade, embodying my invention.

Fig. 2 represents a top, plan view of the same.

Fig. 3 represents a vertical, sectional view, 65 taken upon line 3—3 of Fig. 2.

Fig. 4 represents a sectional view taken on the line 4—4 of Fig. 1, illustrating the method of attaching the holding means to the shield. 70

Referring to said drawing, my improved eye-shade is represented as a whole at A as comprising a main portion 1 of thin flexible, but relatively firm composition cardboard or the like, having a top or forehead margin at 2 and a bottom margin 3. Near the ends of the bottom margins V shaped recesses extending partway only of the width of the main portion 1 and toward the top 2, are formed or cut out of said portion 1, 80 leaving side margins 4 and 5.

The parts adjacent the margins 4 and 5 are overlapped at either side of the main body portion of the shade, the margin 4 in each case extending behind the body portion, 85 as indicated by the dotted lines in Fig. 1 and by full line in Fig. 3.

A binding preferably of fabric, 7, may be secured by stitches 8 or otherwise to the bottom 3. The effect of this overlapping 90 and binding is to first cause the ends of the main part 1 to bend rearwardly to form side walls 9—9 and to cause the lower portion of the main part 1 to bend at an angle to form a substantially vertical wall 10 between and below the points 11—11. The part above the lower wall 10 thus extends upwardly and rearwardly toward the top margin 2. 95

The side walls 9—9 have bottom marginal 100 edges 12 and upwardly and inwardly inclined marginal edges 13 which are merged in a gentle curve at 14, each edge 13 extending upwardly to one end of the top margin 2. The binding, 7, is preferably of a single 105 piece of fabric as shown.

The top margin is covered and protected by a binding of yielding material 15, in this instance of rubber tubing slit lengthwise and, the margin 2 being first inserted in the 110

rubber tube, secured thereto by cement or other suitable means.

Flexible, relatively narrow and thin straps 16 of suitable material such as celluloid or the like, are secured at their ends to the side walls 9-9 near the ends of the top margin 2, by rivets 17 or other suitable means. A buckle 18, secured to one of the free ends of one strap 16 and adapted to receive the free end of the other strap 16 affords adjustable means for locking the straps together and securing the shade to the head of the user. The usual air holes or apertures 19 may be made in the main portion 1, 15 preferably near the rubber binding 15.

When in use my improved eye-shade will be found to have several distinct advantages. In the first place, the inclined front portion 1 and the vertically disposed portion 10 20 extend outwardly from the face of the wearer and do not rest upon the face at all, only the rubber covered margin 2 touching the forehead, and bending in proper curvature as shown in Fig. 2 to conform to the 25 shape of the forehead. The eyes are thus protected more fully from the rays of light because of the downwardly extending portion 10. Again the side walls 9-9 also protect the eyes from rays of light, that otherwise would impinge upon the eyes from the 30 sides and while the side walls do not touch the face along their margins, their upper margins 13 extend substantially to the temples. The flat light retaining bands 16 serve 35 to hold the shade in position without in any degree conveying to the user the feeling of a tight or constricted binding piece about the head and the soft rubber binding member 15 prevents the margin 2 from being 40 pressed into or binding upon the forehead. It also enables the wearer to shift the shade or to adjust it up or down on the forehead without inconvenience or any scraping action. Moreover, the effect as a whole eliminates all sense of a shield or apparatus being worn and after a few minutes in use, the 45 person readily forgets that he has it on.

Again the shape of the parts and the means of securing the same together, with 50 the material used have the additional advantage and utility of being very easy to fabricate at a minimum expenditure both of time and money, thus greatly reducing the cost and bringing the price of the completed article within the reach of the user.

I am aware that automobile goggles have been made, so folded or shaped as to form not only a front wall to shade and guard the eyes, but also side walls at the ends; but

all such structures of which I am aware, are 60 so arranged that their margins completely rest upon the forehead, temples, cheeks and nose of the wearer, completely inclosing and protecting the parts mentioned from wind, dust and objectionable particles of matter 65 which otherwise would strike the face or eye. Such devices would be totally unfitted for use as eye shades, which must be simply a barrier interposed between the eyes and the objectionable rays of light and which 70 must not have any such barrier between the eyes and the object to which the eyes are being directed, such as a book or writing sheet or the like.

I claim as my invention:

1. An eye shade having a downwardly inclined body portion, the lower edge of which is slit on each side of the central line and the portions adjacent the slit arranged in overlapping relation to cause a more abrupt 80 downward inclination of the lower edge of the body, said edge extending in front of and spaced from the face and nose of the wearer.

2. An eye shade having a downwardly inclined body portion, the lower edge of which is slit on each side of the central line and the portions adjacent the slit arranged in overlapping relation to cause a more abrupt downward inclination of the lower edge 90 of the body, said edge extending in front of and spaced from the face and nose of the wearer, and a binding extending along said lower edge and holding the portions adjacent the slits in overlapped relation.

3. An eye shade having a downwardly inclined body portion, the lower edge of said body portion being slit on each side of the central line and the portions adjacent the 100 slits being arranged in overlapping relation to cause a more abrupt downward inclination of the lower edge of the body, and to provide rearwardly-extending downwardly-inclined side portions, the front portion of 105 said shade being spaced from the face and nose of the wearer and the side portions being adapted for engagement with the sides of the head, substantially as described.

In testimony, that I claim the foregoing 110 as my invention I affix my signature in the presence of two witnesses, this 7th day of August, A. D. 1918.

ANDREW RINGMAN.
